UNITED STATES PATENT OFFICE.

ETHAN I. DODDS, OF AVALON, PENNSYLVANIA, ASSIGNOR TO THE PULLMAN COMPANY, OF CHICAGO, ILLINOIS, A CORPORATION OF ILLINOIS.

CAR-DOOR-OPERATING MECHANISM.

No. 820,852.

Specification of Letters Patent.

Patented May 15, 1906.

Application filed May 28, 1905. Serial No. 262,823.

To all whom it may concern:

Be it known that I, ETHAN I. DODDS, a citizen of the United States, residing at Avalon, in the county of Allegheny and State of Pennsylvania, have invented a certain new and useful Improvement in Car-Door-Operating Mechanism, of which the following is a specification.

My invention relates to car-door mechanism, and particularly to such mechanism for opening and closing load-carrying floor-doors of a car which are hinged at one side of the door to points in the car-underframe and are adapted to swing down to discharge the load upon the door.

The object of my invention is to provide a mechanism for raising and lowering the floor-door of a car which can be easily and cheaply made, which is efficient in operation, and not readily liable to get out of order, particularly in the hands of unskilled workmen.

My invention broadly consists in the application of a shaft or other rolling member adapted to bodily travel crosswise or laterally of the car up a slight incline toward the side of the car to raise and lower floor-doors pivoted toward the center of the car and adapted to swing down toward the side of the track on which the car runs to discharge the load upon the floor-door at the side of the track.

My invention, more in detail, consists in the application to such a shaft or rolling member of a spiral cam applied for the purpose of shortening the length of travel of the rolling shaft across the car.

My invention also consists in details of construction, which will be hereinafter more fully described and claimed as the specification proceeds.

The single figure of the drawing represents a vertical sectional view across a car between the cross-bearers or a cross-bearer and a bolster, showing such cross-bearer or bolster in elevation and the details of the application of my invention thereto.

The car shown in the drawing is one of a common type of metallic car having a central girder 10, running lengthwise of the car, intersected or joined at intervals by cross-bearers or bolsters 11, extending from side to side of the car. Rising from the outer ends of these cross-bearers are side stakes 12, con-

nected together by plates 13, forming the sides of the car, box, or body, and thus joining the ends of the cross-bearers or bolsters 11 together and forming them, in connection with the central girder 10, into a unitary rigid underframe. Pivoted at 14 and 15 on opposite sides of the central girder 10 are floor-doors 16, each wide enough to fill the space between successive cross-bearers or cross-bearer and bolster of the car and long enough to, as shown, extend to the side of the car. These doors are, as shown, adapted when in the full-line position of the figure to form substantially the largest part of the floor of the car and to carry the load upon them. The doors are also adapted when swung down to the dotted-line position of the figure to allow the load upon each door to slide off from it at the side of the track. My improved mechanism relates to the mechanical movement of these doors 16 from the dotted-line to full-line position and back to the dotted-line position of the figure, or vice versa.

I have cut or stamped out of each cross-bearer and bolster a slotted opening 20, lower toward the center of the car than it is at the end toward the side of the car. In other words, the slot 20 declines from the side toward the center of the car, as shown. I make these slots 20 in each of the cross-bearers on one side of the central girder 10 of substantially the same size and have them in a straight line with each other along the car, so that a shaft mounted in these slots in the cross-bearers or bolsters will always be parallel to the floor of the car when in the same end or other corresponding positions of each slot. This will more fully appear as the specification proceeds. These slots 20 have on their lower slanting sides gear-teeth 22, while the upper sides 23 are made plain inside, but substantially parallel with the tops of the gear-teeth 22. In each slot 20 I mount a pinion 24, having teeth 25 meshing with the teeth 22, heretofore described, and the pinions are made of such a size that they will just fit in between the sides 22 and 23 of the slots with sufficient clearance so that they may travel inside the slots along the rack-teeth 22 from one end of the slots 20 to the other. Through the pinion 24 thus mounted in each slot 20 in each cross-bearer or bolster 11 I place a shaft 26, running either the

entire length of the car or from the middle to each end, and rigidly secure the pinions to said shaft or shafts. At each end of the car I provide means for applying wrenches or 5 ratchet mechanism of any of the common types, so that a workman at the end of the car can rotate the shaft in either direction, as desired. As the pinions 24 are rigidly secured to the shaft 26, it follows that rotating 10 this shaft in one direction will cause it to travel from the upper to the lower end of slot 20, while rotating it in the opposite direction will cause it to travel from the lower to the upper end of the slot 20.

15 Rigidly secured to the shaft 26, adjacent to each cross-bearer and on opposite sides thereof, I rigidly secure spiral cams 30, bearing against the under side of the floor-doors. The cam on each side of the cross-bearer or 20 bolster, as just described, bears upon a different floor-door. From this it will be seen that there is a cam 30 bearing on each edge of each floor-door 16. I prefer to so proportion these cams 30 with reference to the different 25 distances from the pivots 14 at which the cams in different positions bear against the under sides of the doors that the amount of power required to raise and lower the doors applied to the ends of the shaft 26 will be sub- 30 stantially a constant quantity in all positions of the shaft; but this proportion may be varied somewhat without departing from this feature of my invention.

In the operation of the device, assuming 35 that the doors are up or closed, as shown in the full lines of the figure, and that for this reason the shaft 26 is at the upper end of the slot 20 and the cam 30 is in the full-line position of the figure, the operator applies a 40 wrench or other rotating means to the shaft 26 at the end of the car and rotates the same to the right of the figure toward the center of the car. This causes the pinions 24 to travel along the racks 22 until the parts assume the 45 dotted-line position of the figure, with the shaft at the lower end of the slot 20. In thus traveling along the slots the shaft 26 has caused the cams 30 to also rotate to the dotted position, thereby permitting the load 50 upon the floor-doors 16 to cause it to drop down to the dotted-line position shown.

When it is desired to close the doors after the discharge of the load, the operator simply rotates the shaft 26 in the direction indicated by the arrow in the dotted-line position of 55 the figure, and thereby causes the pinions 24 to travel along the racks 22 to the original position with the doors closed. The upper flange or edge 23 of the slot 20 in each cross-bearer holds the pinion in its slot during this 60 operation, thereby making the same perfectly positive.

The doors 16 when in lowered position rest against a stop 31 upon the under side of the cross-bearers or bolsters, thereby preventing 65 the momentum of the descending doors injuring the operative mechanism when it reaches the extreme lower position, as shown.

I do not wish to be understood as limiting myself to the exact details of construction, 70 which may be varied within reasonable limits without departing from my invention.

This patent is intended to embrace only so much of the disclosure made herein as is covered by the claim.

Having thus described my invention, what I claim as new, and desire to secure by Letters Patent, is—

In a car, in combination with an under-frame having load-carrying car floor-doors 80 pivotally mounted toward the center of the car and adapted to swing downwardly from the side of the car, to discharge the load at the side of the car; a shaft extending lengthwise of the car adapted to be bodily rolled 85 crosswise of the car in inclined slots cut in the underframe of the car, said slots being lower toward the center of the car than at the side, racks upon the under sides of said slots, pinions on said shaft adapted to travel in 90 said racks and spiral cams rigidly secured to said shaft adapted to bear upon the under sides of said doors as said shaft is rotated to open and close the doors.

In witness whereof I have hereunto sub- 95 scribed my name in the presence of two witnesses.

ETHAN I. DODDS.
